COMBINATION MOTOR, PUMP, AND FILTER

Walter J. Otto, Wantagh, N.Y., assignor to Julius L. Englesberg, Freeport, N.Y.

Filed Sept. 17, 1970, Ser. No. 25,316

Term of patent 14 years

Int. Cl. D15—02

U.S. Cl. D65—1

FIG. 3

FIG. 4

FIG. 5

FIG. 1 is a side elevational view of a combination motor, pump, and filter showing my new design;

FIG. 2 is a front view;

FIG. 3 is a rear view;

FIG. 4 is a top plan view; and

FIG. 5 is a bottom plan view.

I claim:

The ornamental design for a combination motor, pump, and filter, substantially as shown.
